MATERNITY NIGHTGOWN

Dorothy H. Leary, Waterbury, Conn.

Application August 29, 1940, Serial No. 354,710

1 Claim. (Cl. 2—73)

This invention relates to ladies' garments and more particularly to a slip-on garment especially adapted for use as a maternity nightgown.

One object of this invention is to provide a maternity nightgown of the above nature having adjustable and elastic means at the waistline and neckband portions thereof.

Another object is to provide a nightgown of the above nature in which the waistline is made adjustable in the front and is provided at the rear with elastic stretchable means to allow for free movement of the wearer.

A still further object of this invention is to provide an improved maternity nightgown of the above nature having a minimum number of parts, which will be inexpensive to manufacture, simple in construction, attractive in appearance, easy to put on and adjust to the size of the wearer, and very efficient and durable in use.

With these and other objects in view, which will appear as the description proceeds, there has been illustrated in the accompanying drawings one form in which the invention may be conveniently embodied in practice.

In the drawings:

Figure 1 is a view in front elevation of a garment embodying the features and principles of this invention.

Figure 2 is a rear elevational view of the upper portion of the same.

Figure 3 is an enlarged side sectional view of the upper portion of the same taken on the line 3—3 of Figure 1.

Figure 4 is an enlarged development view of the upper part of the front portion of the garment shown in Figure 1.

Figure 5 is an enlarged development view, similar to Figure 4, of the rear portion of the garment.

Figure 6 is a development view of a girdle used at the waist portion of the improved garment of this invention.

Figure 7 is a side view, partly broken away, of the upper portion of the improved maternity garment.

Referring now to the drawings wherein like reference numerals designate like parts throughout the several views, the numerals 10 and 11 denote the front portion and the rear portion, respectively, of the maternity nightgown. As is usual in the making of garments, a pattern is provided for each portion, and such a pattern, where the sides of the garment portion are symmetrical, is only one half of such a portion. This pattern is laid upon a folded strip of material with one edge thereof lying at the fold in the material, to form the center as indicated by the dotted lines 12 and 13 in the developed views of

the portions 10 and 11 respectively, (see Figures 4 and 5).

Front garment portion

By the use of a pattern, as above indicated, the front portion 10, (see Figure 4) will be cut from a single piece of material to provide shoulder strap portions 14 and 15; a flap 16 extending between these strap portions 14 and 15; underarm portions 17 and 18 which extend outwardly from the straps 14 and 15 below the same which are joined thereto by curved edges 19 and 20 to form a pair of openings for the arms, and having vertical side edges 21 and 22. Below the side portions 17 and 18 of the shoulder straps 14 and 15, the material of the front portion 10 extends outwardly to form the upper edges 23 and 24 of the wider skirt part 25 of the front portion 10 of the garment. The lower edges 23 and 24 are separated from the upper side portions 17 and 18 by "slashes" 26 and 27, cut inwardly from each side edge 28 and 29 of the portion 10, and are disposed substantially at, or slightly above, the waistline of the garment, and form bottom edges 30 and 31 for the side portions 17 and 18, respectively.

Rear garment portion

The rear portion 11 of the garment is similarly cut from a single piece of folded material to provide shoulder strap portions 32 and 33, a neck flap 34, depending side portions 35 and 36 having side edges 37 and 38 respectively; curved edges 39 and 40 joining the straps 32 and 33 to the side portions 35 and 36 respectively, lower edges 41 and 42 for the side portions 35 and 36 respectively, and upper edges 43 and 44 of a wider skirt portion 45, which is separated from the side portions 35 and 36 by "slashes" 46 and 47 respectively. The slashes 46 and 47 are cut inwardly from each side edge 48 and 49 of the garment portion 11 and are disposed substantially at, or slightly above, the waistline of the garment, to be in alignment with the slashes 26 and 27 in the front portion 10.

Girdle

In order to provide a girdle for the improved maternity garment, provision is made of a wide strap cut from a single piece of flexible material and comprising front and rear parts 50 and 51. The girdle, as shown in Figures 1, 2, 3, and 6, is adapted to be stitched to the front and rear portions 10 and 11 of the garment at the waist portion thereof, surrounding the slashes 26, 27, and 46, 47. The front girdle part 50 (see Figures 1 and 6), which is assembled to the garment front portion 10, is provided with a pair of vertically aligned eyelets 52 and 53, which are

preferably formed by making round holes in the material and binding their edges with thread.

In assembling the garment portions 10 and 11, the material below the slashes 26, 27 and 46, 47 and along the upper edges 23, 24 and 43, 44 of the skirt portion is gathered and stitched to the lower edges 30, 31 and 41, 42 of the side portions 17, 18 and 35, 36 respectively, of the upper portion of the garment above the slashes 26, 27 and 46, 47.

Moreover, the neck flap 16 of the front portion 10, is turned inwardly and downwardly to form a front neckband therefor, and secured to the material below the same by two rows of stitching 54 and 55 (see Figure 4), said rows being spaced apart to permit the insertion therebetween, of a pair of adjustable tying ribbons 56 and 57. The ribbons 56 and 57 are stitched at their outer ends to the flap 16 and the material thereunder, as indicated at 58 and 59. An eyelet 60, similar to the eyelets 52 and 53, is formed at the center of the neck flap 16, provides means through which the free ends of the ribbons 56 and 57 may be passed outwardly in front of the garment portion 10 to permit adjustment of the front of the neckband.

The neck flap 34, of the rear garment portion 11, is also turned inwardly and downwardly to form a rear neck band therefor, and is stitched to the material thereunder by two rows of stitching 61 and 62 (see Figure 5). The stitchings 61 and 62 are spaced apart to permit the insertion therebetween, of a length of elastic tape 63 which is secured at its ends to the ends of the flap 34 as by stitchings 64 and 65. The elastic tape 63 is shorter than the length of the flap 34 so that, when in place, it will cause the material of the garment portion 11 and the neck flap 34 to be gathered together in folds to form a rear elastic neckband, which is stretchable under stresses imposed thereon by movements of the wearer of the garment.

Assembly

In assembling the garment the girdle portions 50 and 51 will be secured to the front and rear garment portions 10 and 11 by rows of spaced apart front stitchings 66, 67 and 68, 69 and rear stitchings 70, 71 and 72, 73 (see Figures 1, 2, and 6). Before applying the girdle portion 50 to the front garment portion 10, it will be understood that the tying ribbons 74, 75, 76, and 77 will have been disposed between the spaced apart stitchings 66, 67, 68 and 69 respectively. The outer end of each ribbon is stitched to the front garment portion and the girdle portion as at 78, 79, 80 and 81, respectively, the free ends of said ribbons 74 and 75 being threaded outwardly through the upper eyelet 52, while the free ends of the ribbons 76 and 77 are being threaded outwardly through the lower eyelet 53. By means of this arrangement, the garment front portion 10 may easily be adjusted and fitted comfortably to the wearer by means of the tying ribbons 74, 75 and 76, 77.

In order to form a stretchable rear waist portion of the garment, a pair of elongated elastic tapes 82 and 83 are disposed between the rows of stitching 70, 71 and 72, 73 (see Figures 2 and 3), during the assembly of the rear girdle portion 51 to the rear garment portion 11. The inner ends of the elastic tapes 82 and 83 are each secured to the girdle portion 51 and the garment

portion 11 by stitchings 84 and 85. The elastic tapes 82 and 83 are made shorter than the developed dimension between the side edges 31, 48 and 38, 49 of the rear garment portion 11, so that when in place, they will cause the material of the garment portion 11 to be gathered together in folds at, or closely adjacent to, the waist of the garment and allow stretching at this point under the stresses imposed by the movements of the said wearer.

The front and rear garment portions 10 and 11 prepared as above outlined, are next secured together at their sides as by stitching along the edges 21, 38, and 28, 49, and 22, 37, and 29, 48 to form seams 86 and 87 as indicated in Figure 7. The ends of the shoulder straps 14, 33, and 15, 32, are also secured together as by stitching at 88 and 89 as indicated in Figures 1 and 3. The garment is now fully assembled and ready for use.

One advantage of the present invention is that due to the elastic rear neckband and elastic rear girdle portion, the garment at these points resiliently fits against the wearer's body in an attractive and comfortable manner. Moreover, due to the adjustability of the front neckband portion and of the front waistband portion by means of the above mentioned tying ribbons, the garment may be easily fitted to the wearer's body and maintained in an attractive and comfortable manner at all times. Furthermore, the use of slashes at the junction between the wide skirt and narrow upper part of the garment, eliminates objectionable bulges of material at this point permitting the garment to hang in attractive folds, without undue stretching of the material.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claim.

Having thus fully described the invention, what is claimed as new and for which it is desired to obtain Letters Patent, is:

A slip-on closed maternity nightgown having integral waist and skirt sections comprising front and rear portions of similar shapes permanently stitched together at the sides thereof, said skirt sections being substantially larger than said waist sections, said front and rear portions at the junction of said waist and skirt sections being provided with V-shaped slashes extending inwardly from the side edges thereof to provide fullness, and the upper edge of said wider skirt section being gather-stitched to the lower edge of said waist section at said slashes, a wide hollow band embracing the front portion of said nightgown at the waistline and covering said slashes, a similar wide hollow band embracing the rear portion of said nightgown at the waistline, adjustable tying tapes positioned in said front band, and being secured at the side ends thereof, said tying tapes passing outside of said band at the center thereof, and stretchable elastic gathering tapes positioned in said rear band and secured to both ends thereof.

DOROTHY H. LEARY.
